UNITED STATES PATENT OFFICE.

CLINTON B. KERNS, OF COPPERHILL, TENNESSEE.

AUTOMATIC STOP FOR PHONOGRAHS.

1,411,732.

Specification of Letters Patent.

Patented Apr. 4, 1922.

Application filed October 11, 1920. Serial No. 416,066.

To all whom it may concern:

Be it known that I, CLINTON B. KERNS, a citizen of the United States, residing at Copperhill, in the county of Polk and State of Tennessee, have invented certain new and useful Improvements in Automatic Stops for Phonographs, of which the following is a specification.

This invention relates to improvements 10 in automatic stops for phonographs.

An important object of the invention is the provision of an automatic stop for phonographs which is extremely simple in construction, while yet functioning to effect a 15 positive stop at a predetermined point.

A further object of the improved automatic stop, is the provision of a stop which can be readily attached to a phonograph, and embodying adjustable means to make 20 the same function correctly.

A further object of the invention is the provision of an automatic stop for phonographs, which is adapted to be installed upon that type of phonograph having the 25 tone transmitting arm force fed laterally across the turntable.

Other objects and advantages of the automatic stop will be apparent during the course of the following detailed description.

30 In the accompanying drawings forming a part of this specification and in which like reference characters designate like parts throughout the same,

Figure 1 is a plan view of a phonograph 35 showing the automatic stop attached thereto.

Figure 2 is a fragmentary cross sectional view of a phonograph showing the automatic stopping means attached thereto.

Figure 3 is a fragmentary cross sectional 40 view showing the relation of the tone arm to the stopping mechanism.

Figure 4 is a fragmentary side elevational view of a detail shown in Figure 3.

In the drawings, wherein for the purpose 45 of illustration is shown a preferred embodiment of my invention, the letter A designates the phonograph, upon which is mounted the turn-table B, to rotate a record C, preferably of the disc type, and which phonograph has embodied therein a tone arm D, preferably of the laterally force fed type, such as the "Edison diamond disc". The 50 automatic stop E is shown associated with the phonograph A for arresting the rota-

tional movement of the turntable when the tone arm reaches a predetermined point.

The phonograph A preferably comprises the side panels 11 forming the cabinet, and having a platform 12 mounted therein in any suitable manner, which supports the turntable platform 13 in any suitable manner. The tone arm D is of the lateral force fed type, and comprises the reproducer 15 upon which the record engaging point 16 is mounted for the purpose of reproducing 65 sound and transmitting the same through the tone arm D, and into the cabinet (not shown). In the type of tone arm shown in the drawings, the same does not depend upon the record engaging needle, in order to 70 convey the reproducer laterally across the record, but the tone arm is force fed to assume the positions as indicated in Figure 1 of the drawing in full and dotted lines, the depending portion 17 of the tone arm D 75 traversing laterally a curved path such as that shown by the dot and dash line 18 in Figure 1 of the drawings. The tone arm operating lever 20 is pivotally positioned upon the turntable platform 13, and is provided for the purpose of lifting the reproducing needle off of the record, for the purpose of swinging the tone arm laterally to assume the idle position as shown in dotted lines in Figure 1 of the drawings, this type 80 of lever being employed upon the Edison type of phonographs. A trip lever 21 is likewise embodied upon the phonograph, which is for the purpose of releasing a brake mechanism (not shown) to arrest rotation 90 of the turn-table B. A suitable starting lever 22 is likewise positioned upon the turntable platform 13, for the purpose of checking the brake mechanism to allow rotation of the turn-table.

The automatic stop E comprises a lever arm 25 which is pivotally connected at 26 by a screw, rivet, or the like to the platform 12, and spaced therefrom by a pillow block 27. The lever arm 25 extends diagonally across the turn-table platform 13, and beneath the turn-table B in order to project slightly at its free end 28 from the turn-table B. An aperture 29 is provided in the projecting end for the connecting of a wire link 30 having the looped end 31 thereon for the reception of the upstanding ear 32 provided upon the brake trip lever 21. An 100 105

indicating arm 33 is provided to be pivotally connected to the lever arm 25 near its pivoted end 26; and comprises, a portion 35 having the end 36 thereof adapted to overlie 5 the record, and turn-table B, to indicate or point out any groove thereupon. A laterally curved extension 37 is provided adjacent the pivoted end of the indicator 33, and projecting in a direction toward the tone 10 arm D. The surface of the curved extension disposed adjacent the tone arm, is curved, and notched to provide the teeth 38 thereupon. An adjustable clamping sleeve 40 is provided to engage about the depending end 15 17 of the tone arm D, and is maintained in position, thereupon by a bolt 41, extending through laterally projecting ears 42 of the sleeve. A projecting tooth, or lug 43 is struck from the material forming the sleeve 20 structure 40 and preferably oppositely disposed from the bolted connection. However at this point a suitable tooth or similar projection may be welded, or soldered to the sleeve 40 to replace the projection 43 if de- 25 sired.

The sleeve 40 is positioned upon the tone arm, in such a position that the extension tooth 43 thereupon will engage with one of the teeth 38 upon the curved extension 37 30 of the indicating arm 33, the particular tooth which the projections 43 engages, of course depends upon the position which the pointer section 35 of the indicator arm 33 assumes with respect to the record C.

35 In operation, since in the majority of cases where it is preferred to stop a record, is immediately upon cessation of the selection. Thereupon, the pointed end 36 of the indicator arm 33 would assume a position 40 directly over the last groove 45 of the record, thus simultaneously moving the curved extension 37, since the same is integral with the pointer 35. As the tone arm moves over the record, and within the phonograph A, from 45 the starting position as illustrated in dotted lines in Figure 1 of the drawing, the rearward part of the tone arm will traverse a path as designated by the curved dot and dash line 18. Upon the reproducing needle 50 16 reaching the last groove in the record, the tooth 43 upon the adjustable sleeve 40, will engage with a tooth 38 upon the curved extension 37, and a force will be exerted through said curved extension 38 directly in 55 line toward the pivot 34, and the lever arm 25 will consequently be shifted slightly, in such manner that the forward end 28 thereof will exert a pull upon the linked connection 30, to trip the lever 31, and release the braking mechanism (not shown) to arrest rotation of the turn-table B, thus stopping the 60 playing of the record.

The closer the last groove 45 in the record is with respect to the pivot 46 of the turn-table, the greater of course will be the travel

of the tone arm D; and consequently it follows that the farther apart they are the travel of the tone arm will be decreased. In order to insure the stopping of the record after the last groove, when the indicator 70 points to the same, the curved extension 37 has been struck from such a radius, and pivoted at such a point upon the lever 25, that upon movement of the indicator or pointer from the pivot 46, successive teeth 38 upon 75 the curved extension 37 will be brought into direct alignment with the extending tooth 43 upon the sleeve 40, which will result in the desired stopping of the record, at any pre-determined point for which the indicator is 80 set.

It is to be understood that the form of my invention herewith shown and described is to be taken as the preferred example of the same, and that various changes in the shape, size and arrangement of parts may be resorted to without departing from the spirit of the invention or the scope of the subjoined claims.

I claim:

1. In an automatic stop for phonographs, the combination, with a phonograph, comprising a turn-table, a tone arm, and brake trip lever, of a lever arm pivotally mounted on said phonograph and engaging the brake trip lever, an indicator arm pivoted upon said lever arm, and overlying the turn-table, and adjustable means carried by said tone-arm and adapted to engage said indicator arm at a point in the movement of said tone 90 arm, determined by said indicator arm, for moving the lever arm to operate the trip brake and arrest motion of the turn-table.

2. In an automatic stop, the combination, with a phonograph having a tone arm, a trip brake lever, a rotatable turn-table, and a record, positioned upon the turn-table, of a lever arm pivotally connected to said phonograph, a link connecting a free end of said lever arm and said brake trip lever, an indicating arm pivoted to said lever arm, and overlying said record for assuming various positions thereon, said indicating arm having an extending arm rigid therewith and projecting laterally therefrom, and an adjustable projection carried by said tone arm, and adapted to engage said lateral projection of the indicating arm upon movement of the tone arm to a position determined by said indicator, to move said lever arm to 100 operate the trip brake lever and arrest movement of the turn-table.

3. In an automatic stop for phonographs, the combination with a phonograph having a laterally force fed tone arm, a turn-table, and a brake trip lever, of a lever arm pivotally mounted upon said phonograph and engaging said brake trip lever, an indicator arm adapted to overlie said turn-table, and connected to said lever arm, and adjustable 115 120 125 130

means carried by said tone arm adapted to engage said indicating arm at the end of the lateral movement to move the lever arm and operate the trip lever to arrest movement of the turn-table.

4. In an automatic stop for phonographs, the combination, with a phonograph having a laterally force fed tone arm, a rotatable turn-table, and a brake trip lever, of a lever 10 arm pivotally connected rearwardly of said tone arm to the phonograph, and having its free end engaging said brake trip lever, an indicator arm pivotally connected to said lever arm, and means carried thereby and 15 by said tone arm for engagement to exert a force in a line parallel to said lateral tone arm movement, to move said lever arm for operating the brake trip lever to arrest rotation of the turn-table.
- 20 5. In an automatic stop for phonographs, the combination, with a phonograph having a laterally force fed tone arm, a rotatable turn-table, and a brake trip lever, of a lever arm pivotally connected to said phonograph, 25 a link connecting the free end of said lever arm to said brake trip lever, an indicating arm pivotally connected to said lever arm,

comprising a pointer portion adapted to overlie a record, and a curved extension having teeth upon the outer face thereof, 30 said indicating arm adapted to be moved to indicate various parts upon the record, and move successive teeth toward said tone arm, and means carried by said tone arm, adapted to engage a tooth upon said curved extension, when said tone arm has assumed a predetermined position upon the record as indicated by said pointer arm, for exerting a force in direct alignment with the pivot connection of said indicating arm and said lever 40 arm, for the purpose of moving said lever arm to release the brake trip lever, and arrest rotation of the turntable.

6. In an automatic stop for disc record playing phonographs, the combination with 45 a brake, and a force fed tone arm, of means connected to said brake for adjustment to indicate grooves on a disc record being played on said phonograph, and means on said force fed tone arm for moving said 50 first mentioned means to actuate said brake at a predetermined point as indicated by said first mentioned means.

CLINTON B. KERNS.
